UNITED STATES PATENT OFFICE.

HARRY CARROLL MERRIAM, OF INDIANAPOLIS, INDIANA, ASSIGNEE TO AMERICAN CARBURETER CO., OF INDIANAPOLIS, INDIANA, A CORPORATION OF INDIANA.

CARBURETER.

1,225,466.

Specification of Letters Patent.

Patented May 8, 1917.

Application filed March 22, 1916. Serial No. 85,886.

To all whom it may concern:

Be it known that I, HARRY C. MERRIAM, a citizen of the United States, and a resident of Indianapolis, in the county of Marion and State of Indiana, have invented certain new and useful Improvements in Carbureters, of which the following is a specification.

My invention relates to carbureters for use with internal combustion engines and is an improvement over the form shown and described in my Letters Patent No. 1,187,463, issued to me on the 13th day of June, 1916.

One of my principal objects is to effect a maximum saving in fuel by causing the same to be broken up as it emerges from a nozzle, and to insure a thorough saturation of air at all engine speeds through the manner of introducing the air around a nozzle.

Another object is to derive maximum power from all points of economy saving and by minimizing friction in the air passages. Also by means of dampers of a peculiar construction which are adapted to open in the degree of engine requirements and in a progressively easier manner due to their manner of mounting, thereby assuring low vacuum so necessary to obtain maximum power and uncommon to the conventional carbureter of spring and weight type.

A further object is to provide a plurality of venturis which are successively brought into action according to engine requirements, whereby perfect acceleration is accomplished and the correct amount of fuel is delivered, this being essential to prevent the engine from choking or loading.

A further object is to provide a supplemental control whereby an initially rich mixture is provided for starting, and further objects are to provide such carbureters which are simple in construction, assembling, and installation, which are well adapted to the purposes for which they are designed, which are composed of few parts not likely to get out of order, and which are comparatively inexpensive.

My invention is fully described in the following specification, of which the accompanying drawings form a part, in which like characters refer to like parts in each of the views, and in which:

Figure 1 is a section taken through a car-

bureter constructed in accordance with my invention, on the line 1—1 of Fig. 3;

Fig. 2 is a section taken on the line 2—2 of Fig. 1;

Fig. 3 is a section taken on the line 3—3 of Fig. 1; and Fig. 4 is a fragmentary detached view of a detail.

Referring to the drawings, 5 represents a casing divided into a float chamber 6, a mixing chamber 7 having a pipe 8 leading to the manifold intake of the engine and in 65 which is a butterfly-valve 9, and an air chamber 10 to which air is led through a pipe 11.

The gasoline is led through a nipple 12 carried by a collar 13 held on a plug 14 by 70 means of a nut 15, said plug having bores 16 and 17 joining the interior of the collar 13 with the interior of the float chamber 6.

Within the chamber 6 is a vertically movable float 18 upon the upper surface of 75 which two weights 19 rest, said weights being carried by levers 20 pivoted to a removable cover 21 of the chamber 6 at 22 and the inner ends of said levers bear against the under side of a flange 23 upon a needle valve 24 normally closing the bore 17 and guided in the cover 21, a cap 25 being provided for said valve on said cover, and the float chamber has a pipe 26 connected with the lower part thereof and which pipe extends beneath 85 the mixing chamber 7, a screw threaded plug 27 closing the outer end of said pipe.

The pipe 26 is pierced by a nozzle 28 threaded thereinto and assembled through an opening 29 closed by a plug 30, this 90 nozzle being arranged within a venturi 31 adjacent the float chamber 6 in communication with both the air and mixing chambers 10 and 7, respectively through a constricted passage of least diameter in the position of 95 the upper end of the nozzle 28.

The nozzle 28 is normally closed by means of a needle valve 32 having a hemi-spherical flange 33 thereon slightly above the nozzle and guided in a plug 34 in the upper surface of the casing 5, and said needle valve 32 carries a hemi-spherical flange 35 intermediate its length serving as a bearing for a spring 36 interposed therebetween and the under side of the upper portion of the casing 5 whereby the needle valve is normally held in lowermost position, though yielding.

Arranged on the axis of the outlet pipe 8 is a nozzle 37 piercing the fuel pipe 26 and assembled through an opening 38 closed by a plug 39, and said nozzle 37 is normally closed by means of a needle valve 40 provided with a hemi-spherical flange 41 slightly above the nozzle 37 and slidably mounted in a block 42 in pivotal connection with one end of a lever 43, a spring 44 being interposed between said lever and hemi-spherical flange 41 to maintain the needle valve 40 in lowermost position, though yieldingly.

The opposite end of the lever 43 rests upon a transverse pin 45 in a threaded rod 46 engaged in a nut 47 vertically movable in the upper portion of the casing 5, a coil spring 48 maintaining lever engagement with said pin, and said lever 43 is provided with a bore for the passage of the needle valve 32, the flange 35 bearing on the upper surface of the lever 43, and it will be noted that by rotating the nut 47 the relationship between the needle valve 32 and the nozzle 28 may be adjusted and lifting the nut 47 will open the nozzle 28 to provide an initially rich mixture for engine starting without changing the said relationship other than for the moment said nut is held raised.

Within the casing 5, between the chambers 7 and 10, are two partition plates 49 and 50 carrying pivots 51 and 52 for two leaf members 53 and 54 normally in horizontal arrangement and the inner ends of which touch to form a partition between the chambers 7 and 10, but the contacting edges thereof are jointly provided with a circular opening for the passage of the needle valve 40, and it will be noted that no air may pass from the chamber 10 to the chamber 7 when these leaf members are in normal positions, nor can any gasoline escape from the nozzle 37 when the needle valve 40 is in its normal nozzle closing position.

Each of these leaf members 53 and 54 carries a damper, 55 and 56 respectively, extended from side wall to side wall of the casing 5, as do also the plates 49 and 50 and the leaf members 53 and 54, these dampers being curved eccentrically of the respective pivots 51 and 52 and having depending wings 57 and 58, the inner surfaces of each of which is arcuated and progressively enlarged from the contacting edges of the plates 49 and 50 to provide a gradually enlarged space between said dampers and depending wings as the leaf members are gradually swung upwardly on their pivots for a reason later pointed out, thereby providing a venturi of gradually increasing diameter.

As the dampers 55 and 56 are raised the links 59 and 60 pivoted at 61 and 62 to the respective leaf members 53 and 54 and to the lever 43 and to each other at 63 raise the

needle valve 40 to allow the gasoline to escape from the nozzle 37 correspondingly and at the same time admitting air to the mixing chamber 7 around the nozzle 37 and between the edges of the leaf members 53 and 54, the degree of needle valve opening being less than the degree of leaf member movement at their adjacent edges because of the difference of radii of the arcs described by the said edges and the pivots 61 and 62, and this needle movement becomes progressively less with the same leaf member movement as the pivots 61 and 62 approach the vertical axial planes of the pivots 51 and 52, thereby impoverishing the mixture as the speed of the engine increases, and this relationship of the pivots 61 and 62 and 51 and 52 renders the leaf member movement progressively easier as the latter are raised.

In Figs. 1 and 4 I have shown extensions to the needle valves in the fuel nozzles consisting of a rod 64 on each valve carrying a spider 65, or ported disk, at its lower end, this serving as guiding means for the respective valve, but I do not confine myself to the use thereof as any suitable equivalent may be employed.

When the butterfly-valve 9 is partly opened, the desired relationship between the nozzle 28 and needle valve 32 having previously been attained by means of the nut 47 on the threaded rod 46, the gasoline is sucked out of the nozzle 28 and, striking against the rounded surface of the flange 35, is broken up and saturates the air passing upwardly around the nozzle 28 on its way to the pipe 8 and to the engine.

When the butterfly-valve continues to open and the demand for fuel becomes too great for the venturi 31 to supply the partition plates 53 and 54 and connected dampers 55 and 56 rise in accordance with the demand, thereby raising the needle valve 40 and causing an opening to be formed around the nozzle 37, and this provides a supplemental supply of the mixture in the degree of damper and needle valve 40 opening, said dampers forming a supplemental venturi of gradually increasing diameter as the engine demand increases.

As hereinbefore stated, the ratio of oil supply and air supply between the dampers as they continue to open changes, more air and less gasoline being progressively supplied, and great economy of gasoline results while the engine is at maximum efficiency at the different speeds, but the valve 40 may be vertically adjusted by means of nuts 66 whereby more or less gasoline may be supplied.

In venturi 31 the mixture is greatly enriched in the progressive needle valve opening, but in the supplemental venturi the mixture is gradually impoverished as the speed of the engine increases and the en-

gine demand for fuel becomes greater and, in starting, the nut 47 may be manually lifted to cause an initially rich mixture without in any way altering the predetermined adjustments.

My carburetor is thoroughly practical, substantially fool-proof, and entirely automatic in action to comply with the engine demands and, while I have shown a preferred embodiment thereof, I may change the details shown and described provided such changes do not depart from the spirit of the invention or the scope of the appended claims.

Having fully described my invention, what I claim as new, and desire to secure by Letters Patent, is:—

1. A carburetor, comprising an oil supply, a plurality of nozzles in communication therewith, a valve for each nozzle, means for leading air around each nozzle, two pivoted dampers embracing one of said nozzles adapted to be raised by a demand of an engine, and links connecting said dampers pivotally with the respective valve to open the latter as said dampers are raised to increase the air supply.

2. A carburetor, comprising an oil supply, a plurality of nozzles in communication therewith, a valve for each nozzle, means for leading air around each nozzle, two pivoted dampers embracing one of said nozzles and provided with surfaces eccentric to their pivots whereby said dampers are gradually separated from each other and from said nozzle when raised from normal positions to increase the air supply, and links connecting said dampers pivotally with the respective valve to open the latter as said dampers are raised to increase the air supply.

3. A carburetor, comprising an oil supply, a plurality of nozzles in communication therewith, a valve for each nozzle, means for leading air around said nozzles, two pivoted dampers embracing one of said nozzles and provided with surfaces eccentric to their pivots whereby said dampers recede from each other and from said nozzle when raised from normal positions to increase the air supply, and links pivoted to said dampers adjacent their pivots and to said valve of said nozzle whereby said valve will be raised in gradually decreased degree as said

dampers are progressively raised to increase the air supply and thus impoverish the mixture at increasing engine speeds.

4. A carburetor, comprising a casing, an oil supply, a plurality of nozzles in communication therewith, means for leading air around said nozzles, a partition arranged horizontally in said casing consisting of oppositely directed plates, and a leaf member pivoted to each plate and normally touching each other at their outer edges and embracing one of said nozzles, a valve for each nozzle, and means for raising the valve of said embraced nozzle when said leaf members are raised, thereby increasing the supply of the fuel mixture.

5. A carburetor, comprising a casing, an oil supply, a plurality of nozzles in communication therewith, a valve for each nozzle, means for leading air around each nozzle, a partition in said casing consisting of oppositely directed plates and normally contacting plates pivoted to said first named plates and embracing one of said nozzles, means for raising the valve of said embraced nozzle when said contacting plates are raised, and means for providing a circular venturi around said embraced nozzle consisting of dependent wings of interior arcuate formation the radius of which is progressively increased downwardly, whereby a gradually increasing diameter of said venturi results as said contacting plates are raised to increase the air supply.

6. A carburetor, comprising a casing, an oil supply, a plurality of nozzles in communication therewith, a valve for each nozzle, means for leading air around said nozzles, means for adjusting one of said valves with respect to its nozzle, means for increasing the air supply and for gradually increasing the oil supply at the other nozzle in a decreasing proportion, and a lever in pivotal connection with said first named valve, with said adjusting means, and with the valve of said last named nozzle whereby the opening of the valve of said last named nozzle will raise the valve of said first named nozzle in the degree of engine requirement.
